GUTTER SCRAPER

Eugene C. Ferris, Harvard, Ill., assignor to Starline Inc., Harvard, Ill., a corporation of Illinois

Application March 25, 1936, Serial No. 70,727

3 Claims. (Cl. 15—236)

An object of this invention is to provide an efficient and inexpensive scraper for use in cleaning the side walls of gutters of cattle barns and the like. These gutters are located at the rear of the cow stalls and have flat bottoms and parallel vertical walls. It is comparatively easy to clean the bottom of the gutter with a shovel, but it is not so easy to clean the side walls of the gutter. The result is that a hard deposit accumulates on the side walls of the gutter which is difficult to remove. The statutory requirements are making it more and more imperative to more thoroughly clean all parts of the cow stall. This invention is provided to overcome this difficulty.

15 This and other objects, as will hereinafter appear, are accomplished by this invention which is fully described in the following specification and shown in the accompanying drawing, in which—

20 Figure 1 is a perspective view of a gutter shown partially in cross section with one embodiment of the gutter scraper placed therein in operative position;

25 Fig. 2 is an enlarged horizontal section on the broken line 2—2 of Fig. 1;

Fig. 3 is a front elevation of a modified form of scraper;

Fig. 4 is a section on the broken line 4—4 of Fig. 3;

30 Fig. 5 is a front elevation of still another modified form of the scraper;

Fig. 6 is a section on the broken line 6—6 of Fig. 5; and

Fig. 7 is a perspective view of a modified form 35 of scraper.

The embodiment shown in Fig. 1 comprises a cow stall having a floor 10 which may be divided up into cow stalls by means of partitions 11, the top of which is shown broken away. At 40 the rear of the cow stalls is a runway 12, preferably at a lower level than that of the cow stalls, and separated therefrom by a gutter 13 which has a bottom 13^a and side walls 13^b, 13^c. These side walls are preferably vertical, parallel and equidistantly spaced from each other. The stall runway and gutter are preferably made of concrete.

45 As previously stated, it is comparatively easy to clean the bottom of the gutter but much of the material in the gutter clings to the side walls and is removed therefrom with difficulty. This material in time becomes very hard. The three forms of scrapers herein illustrated are adapted to remove it.

50 The scraper shown in Figs. 1 and 2 comprises

a central member 14 to which is secured a socket or the like 15 as by riveting, spot-welding, brazing, or the like, and a handle 16 is secured thereto which is preferably placed at an angle to the central member. Lateral extending members 17, 18 are made of spring material and are adjustably secured to the central member as by means of bolts 19 which extend through holes in one of these members and through horizontal slots 20 in the other, and are secured thereto by means of wing nuts 21 or the like. These laterally extending members are preferably provided with spaced slots 22 at their outer edges so as to provide a series of scraper fingers 23. The members 17, 18 are also preferably made as high as the higher vertical walls 13^c so that either side of the scraper may be used to scrape either wall.

In use the scraper is placed in the gutter to be cleaned and the side scrapers adjusted by means of wing nuts 21 so as to substantially fit in the gutter as illustrated, the scraper resting upon the bottom of the gutter. The operator then grasps the handle 16 and moves the scraper forward and backward thereby breaking loose from the sides of the gutter any accumulated matter and thoroughly cleaning these sides. This will usually be done after the gutter has first been roughly cleaned by means of a fork or shovel.

55 In Figs. 3 and 4 is shown a modified form of the scraper in which the central portion 114 is similarly provided with a handle 116, and has laterally extending members 117, 118 which are provided with rivets 119 which are loosely fitted at each side in slots 120. These lateral members 35 are provided with upstruck ears 117^a, 118^a having openings through which pass rods 124. A compression spring 125 surrounds each of these rods and serves to press the lateral members outwardly. Thus as this scraper is moved backward 40 and forward in the gutter, its laterally extending fingers 123 are forced into contact with the sides of the gutter and serve to scrape free any material deposited thereupon.

60 In Figs. 5 and 6 is shown still another modification of the invention having a central member 214 provided with a handle 216 and to which are hingedly mounted lateral members 217, 218. These are preferably provided at their side edges with fingers 223. The member 214 has a U-shaped member 226 secured thereto as by means of rivets or spot-welding. Rods 227, 228 pass through openings in opposite sides of the member 226 so as to be guided therein and are hingedly connected at their outer ends to ears 229, 230 55

respectively which are carried by the lateral members 217, 218. The rod 227 is threaded and has a nut 231 screwed therein so as to serve as a stop to limit the outward movement of its member 217. A spring 232 presses against the nut 231 and urges it toward its outermost position in contact with the member 226. The rod 228 is similarly provided with a nut and spring.

Thus it will be seen in the embodiment shown in Figs. 5 and 6 the scraper members are hinged- 10 ly and yieldingly mounted on the central member, and are provided with means for adjusting the scraper members to different widths of the gutters.

15 In Fig. 7 is shown a modified form of scraper having a body 314 and a handle 316. Scraper disks 317 are each provided with shafts 318 which are journaled in suitable bearings in the body and are slideable endwise therein, and have scrap- 20 er wires or fingers 319 adapted to engage the side walls of the gutter as shown. A spring 320 fits over reduced portions of the shafts and bears at each end on each shaft and is adapted to yield- 25 ingly press the brushes outwardly into contact with the gutter side walls. Thus, as the scraper is moved back and forth, the brushes slide or rotate over the side walls of the gutter and serve to clean these walls of materials deposited there- on.

30 In some cases, the gutter, instead of being level on the bottom, slopes toward the stall floor, as shown in Fig. 7. The scrapers adapt themselves to this condition.

While I have shown and described but a few 35 embodiments of my invention, it is to be understood that it is capable of many modifications. Changes, therefore, in the construction and ar- 40 arrangement may be made which do not depart from the spirit and scope of the invention as dis- closed in the appended claims.

I claim:

1. A gutter scraping device comprising a central body member of a less length than the space between the gutter walls, means supporting said body in scraping contact with the bottom of said gutter and at substantially right angles to the side walls thereof, including a rigid, elongated handle, and relatively rigid side wall scraping elements adjustably mounted on opposite sides of said central member to engage the opposite side walls 10 of said gutter.

2. A scraping device for the spaced side walls of an open top gutter comprising a substantially rigid central member having a non-yielding scraping edge adapted to rest upon the bottom 15 of the gutter, an elongated handle rigidly secured to said central member at an acute angle so as to extend above the gutter walls while supporting the central member in a substantially vertical plane between said walls, and said central mem- 20 ber having a relatively yieldable side wall scraping portion adjustably connected to said central member to extend in substantially the plane of the supporting edge thereof and engage the op- 25 posite side walls of the gutter.

3. A gutter scraping tool comprising an elong- 30 ated rigid handle, a substantially rectangular center plate having an elongated scraping edge, said plate being rigidly connected to one end of said handle so as to extend at an acute angle 35 thereto when supported thereby on said edge in a vertical position on the bottom of said gutter, and other scraper plates adjustably connected to opposite side edge portions of said center plate, said other scraper plates having relatively yield- 40 able outer scraping edge portions supported in substantially the plane of the lower supporting edge portion of said central plate and in engage- ment with the opposite side walls of the gutter.

EUGENE C. FERRIS. 40
